UNITED STATES PATENT OFFICE

EDWARD BAILEY PAGE, OF EASTBOURNE, ENGLAND

BRUSH MAKING MACHINERY

Application filed December 16, 1931, Serial No. 581,283, and in Great Britain January 26, 1931.

This invention relates to brush making machines and has reference to brush stock filling machines such as of the type wherein at each operation a knot of bristles is picked by a picker from storage and transferred to a nozzle through which it is carried forward together with a staple and forced into the previously drilled brush stock or back.

In certain cases it is necessary to change the length or material of the bristles and the object of the invention is to provide a brush making machine with a bristle feeding mechanism so arranged that a knot of bristles may be taken selectively from alternative storages to which the different bristles are fed in the usual manner.

The present invention comprises an automatic bristle or like feeding device for a machine having filler nozzle mechanism and for use in the manufacture of brushes having bristles or like of different material or length in different parts of the brush, wherein in the knots of the different kinds of bristles are fed in succession or in any desired sequence into the respective holes in the same brush stock in a single machine.

In the preferred form of the apparatus each kind of bristle or the like is fed through a separate trough or channel to picker or knotter mechanism for transferring a knot to a filler nozzle, and the selection of the different kinds of bristles to form the respective knots is effected automatically in any desired pre-arranged sequence—which may be changed when desired—by cam or equivalent mechanism operated by the machine. In some forms of the apparatus automatic shutter mechanism is provided to close either trough or channel while the other is delivering bristles or the like to the knotter or picker mechanism.

The picker preferably consists of a rocking member rocked by link mechanism from a continuously moving shaft of the machine and having a circular edge in which is formed a knot forming groove moving transversely to the bristles, and of which the periphery bears against spring pressed surfaces at the side of each bristle feeding trough so that the knot forming groove will

be closed while passing from the bristle feeding trough to the filler nozzle.

A further feature of the invention comprises an automatic bristle or like feeding device for a brush stock filling machine, having a picker or knotter formed by a transverse groove in the circular periphery of a quadrant member rocked continuously to and fro across the open ends of two bristle feeding troughs provided with shutter mechanism adapted to close one trough while opening the other, the picker or knotter being arranged to collect and carry a knot of bristles from one trough under the shutter of the other trough to the filling nozzle by cam and lever mechanism operated by a power shaft of the machine which also operates the shutter mechanism intermittently by ratchet mechanism.

A manner of carrying out the invention is illustrated by the accompanying drawings in which Fig. 1 is a plan of the portion of a brush filling machine showing the main elements of the invention, Fig. 2 is a side elevation of a portion of Fig. 1 and Fig. 3 a front elevation of Fig. 2.

In these drawings *a* is a continuously driven power shaft of the machine, and on the shaft *a* is fixed a cam *a* which reciprocates a lever *a* carrying a roller *a* running in the groove of the cam and pivoted at *a*. The lever *a* is connected at its upper end by a universal joint *a* to a rod *a*. The end of the rod *a* is connected by a universal joint *a* to an arm *a*.

The arm *a* is fixed on the lower end of a vertical shaft *c* rocking in bearings in the standard *h* of the machine. On the upper end of the shaft *c* is fixed a lever *d* carrying a quadrant member *f* having a circular periphery in which is formed a groove *f* which comprises the picker or knotter.

Leading to the periphery of the quadrant member *f* are two parallel troughs or channels *k* and *k* having side walls *k*, *k*, and *k* and each adapted to receive different kinds of bristles or the like standing upright and pushed towards the quadrant members *f* by means of pins *k* and *k*. The pin *k* is mounted in a slide *k* adapted to move in

a slot k_9 provided in the wall k_5 while the other end of the pin k_6 slides in a groove k_{10} provided in the wall k_4 . The pin k_6 is by means of a pin k_{11} extending from the 5 slide k_8 pulled in a direction to feed the bristles to the circular periphery of the picker carrying quadrant member f by means of a cable k_{12} which passes over pulleys k_{13} and k_{14} and carries at its end a weight k_{15} .

10 The bristle feeding pin k_7 is provided with duplicate feeding mechanism for feeding the bristles in the trough or channel k_1 against the circular periphery of the picker of the quadrant f .

15 The above apparatus is applied to brush stock filling mechanism of which m is the filler nozzle and m_3 the stock holder, and during the reciprocation of the quadrant member f by the cam a_1 the groove f_1 forming the picker or knotted is moved across the ends of the troughs k_1 or k_2 and carries with it a collected knot of bristles to the centre of the nozzle shaft m_1 , the usual slot m_3 being provided in the side of m_1 in the usual 20 manner.

In order to close either the bristles feeding troughs k_1 or k while the other is feeding bristles, shutter mechanism is provided consisting of two oppositely disposed fingers 25

30 n_1 and n_2 curved on their inner faces to engage the circular periphery of the quadrant member f containing the picker or knotted groove f_1 , and are held against such surface by springs n_3 and n_4 respectively. The fingers n_1 and n_2 are supported in grooves in 35 detachable blocks n_5 and n_6 respectively, and these blocks are also arranged to bear against the periphery of the quadrant member f . The block n_6 is pivoted to the wall k_3 by a pin n_7 and is turned about this pivot 40 against the circular surface of the quadrant member f by means of a spring n_8 .

The shutter fingers n_1 and n_2 have pivot pins n_9 and n_{10} which run in curved grooves 45 n_{11} and n_{12} in the blocks n_5 and n_6 respectively. These pivot pins also connect the fingers n_1 and n_2 to a quadrant member e having a boss e_5 loosely surrounding the shaft e and on the lower end of the boss e_5 50 is provided an arm e_1 connected by a universal joint e_6 to the end of a lever e_2 pivoted at e_3 to the standard h of the machine. At a point between the ends thereof the lever e_2 is connected by a universal joint e_{26} to 55 the end of a rod e_4 . The other end of the rod e_4 is connected by a universal joint e_7 to the upper end of a lever e_8 pivoted at e_9 to the standard of the machine and carrying at a point intermediate its ends a roller e_{10} 60 adapted to run in a groove e_{11} in a cam e_{12} fixed on a shaft e_{13} . The shaft e_{13} is rotated intermittently by a ratchet wheel e_{14} of which the teeth are engaged by a pawl e_{15} carried by an arm e_{16} loosely mounted on 65 the shaft e_{13} the free end of the arm e_{16}

being also linked by a rod e_{17} to the end of a lever e_{18} pivoted at e_{19} to the standard of the machine and carrying at an intermediate point a roller e_{20} held by a spring e_{22} in engagement with an eccentric e_{21} carried by the cam a_1 . 70

During the rotation of the shaft a the eccentric e_{21} reciprocates the pawl e_{15} and so rotates the cam e_{12} intermittently, and the cam e_{12} reciprocates the lever e_8 and rod e_4 and thereby the lever e_2 which reciprocates the arm e_1 and thereby the quadrant e carrying the shutter fingers n_1 and n_2 . 75

At one end of the movement of the quadrant e the shutter finger n_1 prevents bristles moving from the trough k_2 into the picker or knotted groove f_1 in the quadrant member f , so that the picker or knotted groove f_1 will only carry bristles from the trough k_1 into the recess m_3 of the filler nozzle m , and at the other end of the movement of the quadrant e , the shutter finger n_1 moves away from the trough k_2 while the shutter finger n_2 moves across the trough k_1 so that bristles from the trough k_2 will be taken up by the picker or knotted groove f_1 and so be carried by the quadrant member f under the shutter finger n_2 into the groove m_3 of the filler nozzle m . 80

To ensure the closure of the picker or knotted groove f_1 while carrying a knot of bristles from the trough k_2 past the division wall k_4 of the troughs, a shoe k_{16} is pressed by a spring k_{17} into engagement with the circular periphery of the quadrant f , and for a similar purpose and in a similar manner the block n_6 is pressed against the quadrant f . 85

The reciprocating movement of the shutter carrying quadrant e is limited by adjustable stops s_1 and s_2 . 90

Machines filter with dual bristle feeding arrangements according to my invention will have the manifest advantage that brushes such as scrubbing brushes where the body of the brush has bristles shorter than those at the ends, can be filled on the same machine or brushes with different lengths or qualities of bristles can be filled on the same machine. 110

What I claim and desire to claim by Letters Patent is:— 115

1. An automatic bristle feeding device for feeding bristles to the filler nozzle of a brush stock filling machine, comprising two troughs each containing a different kind of bristle, means for feeding the bristles along to the ends of the troughs, a single means for conveying a knot of bristles from the end of either trough to the filler nozzle, a trough closing shutter for each trough, means for operating both shutters simultaneously across the ends of the troughs, the shutters being operatively connected together so that as one opens one trough the other closes the other trough. 120

2. An automatic bristle feeding device for feeding bristles to the filler nozzle of a brush stock filling machine, comprising two troughs, each containing a different kind of bristle, means for feeding the bristles along to the ends of the troughs, a quadrant member having on its peripheral surface a single knotter groove, a rocking lever carrying the quadrant, means for rocking the lever to both shutters, means for rocking the quadrant member, the axis of the rocking lever and that of the quadrant member being coincident, and means for rocking the quadrant in timed relationship to that operating the lever. 70

3. An automatic bristle feeding device for feeding bristles to the filler nozzle of a brush stock filling machine, comprising two troughs each containing a different kind of bristle, means for feeding the bristles along to the ends of the troughs, a single means for conveying a knot of bristles from the end of either trough to the filler nozzle, two trough closing shutters, a quadrant member carrying both shutters, adjustable stops, and means for rocking the quadrant member between the stops, in timed relationship to the means for conveying a knot of bristles from a trough to the filler nozzle. 80
- 20 25 30 35 40 45 50 55 60 65
4. An automatic bristle feeding device for feeding bristles to the filler nozzle of a brush stock filling machine, comprising two troughs each containing a different kind of bristle, means for feeding the bristles along to the ends of the troughs, a single means for conveying a knot of bristles from the end of either trough to the filler nozzle, two trough closing shutters, a quadrant member, each shutter having a curved slot concentric with the quadrant member, a pin fixed in each opposite end of the quadrant and extending freely through the curved grooves in the shutters, means for guiding the shutters in a curved path, and means for rocking the quadrant in timed relationship to the means for conveying a knot of bristles from a trough to the filler nozzle. 90
- 25 30 35 40 45 50 55 60 65
5. An automatic bristle feeding device for feeding bristles to the filler nozzle of a brush stock filling machine, and comprising two troughs each containing a different kind of bristle, means for feeding the bristles along to the ends of the troughs, a quadrant member having on its peripheral surface a single knotter groove, a rocking lever carrying the quadrant, a means for rocking the lever to convey the knots from the troughs to the filler nozzle, two trough closing shutters, curved surfaces formed on the shutters concentric with and pressed by means of springs against the periphery of the quadrant member carrying the simple knotter groove, a quadrant member carrying 95
- 10 15 20 25 30 35 40 45 50 55 60 65
6. An automatic bristle feeding device for feeding bristles to the filler nozzle of a brush stock filling machine, comprising two troughs each containing a different kind of bristle, means for feeding the bristles along to the ends of the troughs, a quadrant member having on its peripheral surface a single knotter groove, a rocking lever carrying the quadrant, cam lever and link mechanism rocking the lever, a trough end closing shutter for each trough, a quadrant member carrying both shutters, cam lever and link mechanism rocking the quadrant, the cams being timed to operate the quadrant operating link and lever mechanism in timed relationship to that of the lever operating link and lever mechanism so that when one groove is open the other is simultaneously closed in the desired sequence. 100
- 15 20 25 30 35 40 45 50 55 60 65
7. An automatic bristle feeding device for feeding bristles to the filler nozzle of a brush stock filling machine, embodying therein two open ended troughs, each adapted to contain a different kind of bristle, a member having on its perimeter a single knotter groove, means for reciprocating said member across and closely adjacent the open end of both troughs, shutters for said troughs respectively, means simultaneously actuating said shutters, whereby when one shutter is interposed between the bristles in one trough and said member, the other shutter is moved from across the end of the other trough, means automatically moving the bristles in each trough toward the open end thereof, and means automatically timing the actuation of said shutter actuating means so that different kinds of bristles are automatically delivered to the brush nozzle as required during the production of a brush. 105
